(57) **CLAIM**

The ornamental design for a hook, as shown and described.

DESCRIPTION

FIG. 1 is a perspective view of a first embodiment of a hook showing our new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is a partially enlarged view showing the area "8" in FIG. 1;

FIG. 9 is a perspective view of a second embodiment of the hook;

FIG. 10 is a front view thereof;

FIG. 11 is a rear view thereof;

FIG. 12 is a left side view thereof;

FIG. 13 is a right side view thereof;

FIG. 14 is an enlarged top view thereof;

FIG. 15 is an enlarged bottom view thereof; and,

FIG. 16 is a partially enlarged view showing the area "16" in FIG. 9.

The broken lines depict portions of the hook that form no part of the claimed design.

The dot-dash broken lines indicating an enlargement portion of the design form no part of the claimed design.

1 Claim, 16 Drawing Sheets
